CAR DOOR AND OPERATING MEANS THEREFOR

Filed Dec. 22, 1927

Patented Sept. 25, 1928.

1,685,631

UNITED STATES PATENT OFFICE.

FLOYD G. EVANS, OF BATON ROUGE, LOUISIANA, ASSIGNOR OF ONE-HALF TO HARRY W. MITCHELL, OF WEBSTER SPRINGS, WEST VIRGINIA.

CAR DOOR AND OPERATING MEANS THEREFOR.

Application filed December 22, 1927. Serial No. 241,995.

This invention relates to new and useful improvements in door constructions for freight cars and has reference more particularly to a device for operating the doors to open and close the door opening provided in the sides of the freight car.

A further object of the invention is to provide a door construction wherein the operating means therefor is adapted to provide a lock for securing the door in a closed position in one instance, and to provide a means for opening or closing the door in another instance.

A still further object of the invention is to provide a door construction and operating means therefor which is simple in construction, inexpensive, strong and durable and furthermore adapted for the purposes for which it is designated.

Other objects and advantages of this invention will become apparent during the course of the following description.

In the drawings forming part of this specification, and in which like numerals designate like parts throughout the same:

Figure 1 is a side elevation of my invention showing the door in a closed and locked position, and

Fig. 2 is a fragmentary plan view of the door operating means showing the same unlocked and secured in position for opening the door.

In the drawing wherein for the purpose of illustration, is shown the preferred embodiment of my invention, the numeral 1 denotes the side of a freight car preferably of the box car type wherein the same is provided with the usual door opening in the side thereof. For the purpose of closing the door opening, I provide the door 2 and the same is adapted to slide on the side 1 of the car in the manner to be presently described.

Supported in suitable brackets 3 secured to the outer side of the door 2 adjacent the upper edge thereof and adapted to rotate therein are the upper rollers 4. Two of such rollers being provided in the manners clearly illustrated in Fig. 1.

The lower portion of the door is also provided with supporting brackets 5 similar to the bracket 3 above described and adapted to be rotatably supported in one of the lower brackets 5 is the lower roller 6. Supported in the lower bracket at the opposite corner is the ratchet wheel 7 and the purpose thereof will

be presently described. Cooperating with the operating upper rollers 4 is the longitudinally extending guide rail 8 which is secured on the side of the car adjacent the upper edge of the door opening and the same is preferably of angular formation to prevent the door from moving laterally with respect thereto. The guide rail 8 has one portion thereof disposed over the door opening while the remaining portion is arranged on the side of the car for a suitable distance beyond the opening.

For the purpose of cooperating with the lower roller 6 and the sprocket wheel 7, I provide the channel shaped rail 9 which is secured to the side of the car adjacent the lower edge of the door opening in the manner similar to which the upper guide rail is secured adjacent the upper edge of the door opening. The guide rail 9 is provided with a plurality of openings 10 which are arranged in the base portion thereof and are spaced in such a manner as to mesh with the teeth 11 of the ratchet wheel 7, in the manner clearly illustrated in Fig. 1.

It is also to be understood that the lower roller 6 will ride on the rail and the provision of the ratchet wheel with the openings in the lower rail to receive the teeth of the ratchet wheel, will provide a means whereby the door may be moved on the side of the car to open and close the door opening in the manner hereinafter to be more fully described. Vertically extending angular strips 12 and 13 respectively are secured to the sides of the car for limiting the sliding movement of the door, and the strip 12 will engage one of the side edges of the door when the same is in a closed position, while the strip 13 will engage the opposite edge of the door when the same is in an open position.

The outer end of the shaft upon which the ratchet wheel 7 is keyed, is flattened as illustrated at 14, and pivotally connected thereto is the inner bifurcated end of the arm or lever 15. The pivotal connection is illustrated at 16. The outer end of the arm or lever 15 is bifurcated as illustrated at 17 and pivotally supported in the outer end of the bifurcated portion of the lever is the substantially right annular member 18.

The pivotal connection for the right angular member is illustrated at 19. One of the arms 20 of the right angular member 18 is provided with a slot for engagement with a

suitable keeper or staple 21, secured to the side of the car adjacent the door opening and the slotted arm 20 will provide a hasp for cooperation with the staple in receiving a pin 22 of any conventional construction whereby a lock for securing the door in closed position is provided when the right angular member 18 is in the position as shown, in Fig. 1.

The other arm 23 of the right angular member 18 is provided with an opening in the free end thereof for registration with aligning openings 24 provided in the bifurcated portion 17 of the outer end of the arm or lever 15. The pin 22 is then inserted through the registering opening of the bifurcated outer end of the arm or lever 15, and the arm 23 of the right angular member 18, so as to cause the right angular member to have the arms 20 thereof, disposed at substantially right angles to the lever 15 and provide a means for actuating the lever and ratchet wheel whereby the latter may be rotated for engagement with the openings provided in the lower rail 9, thereby enabling the door to be moved out of engagement with the door opening in the manner as is obvious from the construction as shown in the drawing.

With the parts arranged as shown in Fig. 2, of the drawing, the arm 20 of the right angular member 18 provides a handle and by turning the same, the teeth on the ratchet wheel 11 will mesh with the openings 10 provided in the base of the lower guide rail 9 and the door may freely slide between the guide rails until the side edge of the same engages the strip 13, thereby limiting the movement of the door in that direction. To close the door, it is only necessary to reverse the rotation of the ratchet wheel so that the door will again resume the position shown in Fig. 1 and the pin 22 may then be removed from engagement with the registering openings provided in the bifurcated outer end of the arm or lever 15 and the outer end of the arm 23 of the right angular member 18, and by swinging the latter on its pivot 19, the hasp 20 may be brought into engagement with the staple 21 and the pin 22 inserted

therein and a suitable seal placed thereon, 50 whereby the door will be locked closing the door opening.

It will thus be seen from the foregoing description, that a door for freight cars has been provided which is very simple in construction, and the operating means therefor will enable the same to be readily moved to an open or closed position as is desired. Furthermore, the operating means of the door will be strong and durable and may be readily moved for either providing a locking means for the door or to provide a means for moving the same.

While I have shown the preferred embodiment of my invention, it is to be understood that various changes in the size, shape and arrangement of parts may be resorted to without departing from the spirit of the invention and the scope of the appended claims.

Having thus described my invention, what 70 I claim as new is:—

1. In a structure of the class specified wherein the same embodies a ratchet wheel equipped with a rotating stud, a convertible hand crank for rotating said wheel, said hand crank comprising a lever connected to said stud, and a handle pivotally connected to the outer end of the lever, said handle being formed with a slot to permit passage of a staple therethrough, whereby to permit the handle to function additionally as a hasp.

2. In a structure of the class described, wherein the same embodies a ratchet wheel provided with a rotating stud, a convertible hand crank for cooperation with said wheel, 85 said crank comprising a lever pivotally connected at its inner end to said stud and bifurcated at its outer end, and a handle adapted to be disposed at a right angle to the lever said handle being pivoted between the bifurcations and being provided adjacent the free end with a slot through which a staple is adapted to extend whereby to permit the handle to be swung into alignment with the lever to function additionally as a hasp.

In testimony whereof I affix my signature.

FLOYD G. EVANS.
